UNITED STATES PATENT OFFICE.

ARCHIBALD PUTNAM AND JAS. H. PUTNAM, OF WELLSVILLE, OHIO, ASSIGNORS TO THEM-
SELVES AND PHILIP F. GEISSE, OF SAME PLACE.

RAILROAD TURN-TABLE.

Specification of Letters Patent No. 24,522, dated June 21, 1859.

To all whom it may concern:

Be it known that we, ARCHIBALD PUTNAM and JAMES H. PUTNAM, both of Wellsville, Columbiana county, Ohio, have invented a 5 certain new and useful Improvement in Railroad Turn-Tables; and we hereby declare the following to be a full and exact description of the same, reference being had to the annexed drawings, making part of 10 this specification.

Our invention consists in an application of adjustable spindle to compensate for wear and equalize the bearings of the table.

In the accompanying drawings Figure 1 15 represents a perspective view of our improved turn table. Fig. 2 is a side elevation of the same. Fig. 3 is a vertical transverse section at α α Fig. 2.

A A represent trucks mounted on wheels 20 B and supporting the ends of string pieces C. D are base ties running nearly the length of the table and connected to the string pieces C by brace rods F passing through the base ties D and string pieces C, and 25 secured by nuts a , a' .

h , h , are diagonal braces extending between the strings C and base ties upon a similar principle to the truss framing of a bridge. 30 J, J, are tension cords for the purpose of giving additional strength to that part of the table between the bearings. Secured centrally of the table between the string pieces C and base ties D is a cross beam 35 E. This cross beam is of the same length as the table, and is set at right angles thereto and supported at each end on trucks G, G, mounted on wheels b , b . One object of this beam, is to relieve the spindle from

40 some of the weight which would otherwise come upon it; another object is to prevent the table from careening from unequal weight on either side thereby straining the spindle or throwing it out of its proper bearing. 45 H H, are stay rods connecting the ends of the cross beam to the cap plate c.

d d , are sleepers secured transversely upon the string pieces C.

K K are the rails attached to the sleepers 50 in the usual manner.

e in Fig. 3 is a nut fitted centrally in the cross beam E with flange f attached to its lower end; when the said nut is in place this flange is brought in contact with the 55 underside of the cross beam and sustains that portion of the weight upon the screw thread of the spindle.

g is the spindle upon the upper part of which is cut a screw thread which fits into 60 the nut e, by means of which the spindle is adjusted to compensate for the wear of that end working in the step i, and also to adjust the level or the table to correspond with that of the track. 65

L is an annular track upon which the truck wheels run when the table is revolved.

In the ordinary railroad turn table the weakest point is usually between the central and outward bearings, because there being 70 no bearing there, there is nothing to sustain the weight at that point, consequently the table and track with it sag and thereby strain the spindle, whereas by our arrangement of braces it will be seen any undue 75 strain at this point is diagonally transferred to the outward or central bearings, so that the table cannot sag. Should the weight be unequally divided upon the two tracks or in other words more on one side than 80 the other it is prevented from careening as before stated by the cross beam E.

Tables constructed upon this plan can be easily taken apart for transportation.

We claim as new and of our invention— 85

The adjustable spring g applied and adapted in the manner and for the purpose set forth.

In testimony of which invention, we hereunto set our hands.

A. PUTNAM.
